UNITED STATES PATENT OFFICE

THOMAS MIDGLEY, OF HARTFORD, CONNECTICUT, ASSIGNOR TO THE
HARTFORD RUBBER WORKS COMPANY, A CORPORATION OF CON-
NECTICUT.

WHEEL-RIM.

No. 841,801.

Specification of Letters Patent.

Patented Jan. 22, 1907.

Application filed April 29, 1905. Serial No. 258,128.

To all whom it may concern:

Be it known that I, THOMAS MIDGLEY, a citizen of the United States, residing in the city of Hartford, county of Hartford, and State of Connecticut, have invented new and useful Improvements in Wheel-Rims, of which the following is a specification.

This invention relates to wheel-rims, and particularly to rims adapted for use in connection with rubber tires, whether of pneumatic, cushion, or solid types.

The principal object of the invention is to provide a novel construction of wheel-rim in which the qualities of strength, lightness, and cheapness are present in striking degree.

A further object of the invention is to produce a hollow rim of sheet metal in which the parts are securely held without brazing, soldering, or welding.

With the objects above stated and others in view, as will hereinafter appear, the invention consists in a novel construction of rim which is illustrated in two slightly different forms in the accompanying drawings, described in the following specification, and has the novel features thereof clearly pointed out in the claims.

In the drawings, Figure 1 is a transverse section through the rim before the seam has been completed. Fig. 2 is a transverse section through the rim after the completion of the seam, but before the ends are joined. Fig. 3 is a transverse section through the rim on the line 3 3 of Fig. 6, showing the mode of joining the ends. Fig. 4 is a transverse section on the line 4 4 of Fig. 6, showing the reinforcement of the rim where the tire-valve passes through it. Fig. 5 is a transverse section through a rim having a somewhat different seam from that shown in the other figures. Fig. 6 is a fragmentary plan view of the rim at the junction of the ends where the opening for the tire-valve is formed.

Referring to the drawings, in which corresponding parts are designated by similar characters of reference, 1 designates a strip of sheet metal of suitable gage from which the rim is formed. The strip 1 of metal is shaped by means of gang-rolls into the form desired—such, for example, as that indicated in the several figures of the drawings—the edges being brought together on the under

side or wheel-face 2 of the rim. Then the edges are joined in a seam, the seam is flattened on a suitable mandrel which is inserted into the open space 3 within the rim for that purpose, and the mandrel is then withdrawn, so that the rim may be bent around a suitable form to bring the ends together, so that they may join.

In the rim illustrated in Figs. 1, 2, 3, and 4, the edges 4 of the strip of sheet metal are brought together and then turned away from each other to form oppositely-projecting flanges, over which the narrow strip 5 of metal is crimped to secure the edges of the member 1 in position. After the strip 5 has been applied, as indicated in Fig. 1, a mandrel of suitable cross-section is introduced into the space 3 within the rim, and pressure is applied to the strip 5 to flatten the same, as shown in Fig. 2, thus leaving the inner or wheel-face of the rim substantially flat transversely.

After the seam is formed and flattened the mandrel is withdrawn from the interior of the rim, and it is next bent around a suitable form, the rim having previously been cut to the proper length, and the ends of the rim are joined. The joining of the ends of the rim may be accomplished in any suitable manner; but I prefer to insert a filling-piece 6 into both ends and to secure the filling-piece in position by means of rivets 7 passing through both thicknesses of the metal forming the rim and through the filling-piece. The filling-piece 6 is preferably provided with a circular opening 8 in the middle, and semicircular notches 9 must be cut in the ends of the rim, so that when the ends are united, as shown in Fig. 6, the two semicircular notches will register to form the circular opening 8.

The rivet-holes in the filling-piece 6 are deeply countersunk, as clearly shown in Fig. 3, and the metal of both thicknesses of the rim is pressed into the countersunk portions of the rivet-holes, thus affording a very strong connection between the metal of the rim proper and the filling-piece and lessening the liability of the rivets to tear the metal of the rim.

The form of rim illustrated in Fig. 5 is similar to that above described in all respects except the seam, which dispenses with the bind-

ing-strip shown in the preceding figures. In the construction of the rim shown in Fig. 5 a strip of sheet metal may pass through a gang rolling-mill and be converted into substantially the form shown in Fig. 5, the edges not being interlocked, as shown in that figure. The edges of the strip are, however, bent, so as to interlock when brought into engagement, and the nature of the lock so formed is clearly indicated in Fig. 5. The formation of a seam of this character, like that already described, requires the use of a suitable mandrel, which is introduced into the space within the rim, and the bead is then flattened. The rim is then ready for bending and for joining the ends together in the manner above described. In the rims illustrated the construction shown is such that side flanges are required in connection with the rim to afford a suitable seat for a resilient tire, and it is intended that the invention be principally embodied in rims of this character. It is, however, evident that rims of other types may be made in accord with the present invention, and I do not, therefore, limit myself to the exact types of rims shown and described, but reserve the right to make changes therein such as will not exceed the scope of the claims.

Having thus described my invention, what

I claim as new, and desire to secure by Letters Patent, is—

1. A tubular wheel-rim of much greater width than thickness formed of a piece of sheet metal folded longitudinally upon itself to present separate thicknesses for the wheel-face and tire-face and having the edges of the material joined in a longitudinal lock-seam upon the wheel-face of the rim, the thicknesses of material forming the wheel-face and tire-face being spaced apart to present a chamber in the interior of the rim and the wheel-face of the rim being flattened so that the seam projects into the chamber within the rim.

2. A tubular wheel-rim having the ends joined by means of a solid filling-piece enclosed in the interior of the rim and extending into both ends thereof, the filling-piece being secured in position by means of rivets passing through the filling-piece and the material inclosing it, and the metal of the rim being forced into countersunk rivet-holes in the filling-piece.

In testimony whereof I have signed my name in the presence of two witnesses.

THOMAS MIDGLEY.
